PAPER CUTTER

Charles C. Shackelford, West Monroe, La.

Application September 29, 1938, Serial No. 232,473

2 Claims. (Cl. 164—76)

This invention appertains to new and useful improvements in paper driers and more particularly to a cutter mechanism for employment therewith.

5 The principal object of the present invention is to provide a cutter mechanism for use in conjunction with paper driers whereby the cutter can be quickly operated to sever the paper in the event of a jam-up in the drier.

10 Another important object of the invention is to provide a cutter of the character stated which can be quick-acting and not susceptible to the ready development of defects.

15 These and various other important objects and advantages of the invention will become apparent to the reader of the following specification.

In the drawings:

Figure 1 represents a fragmentary vertical sectional view through a group of drier cans showing in section the cutting mechanism.

Figure 2 is a side elevational view of the cutter disk and guard therefor.

Figure 3 is a cross sectional view of one of the cutter assemblies.

20 Figure 4 is a sectional view through one of the guards.

Figure 5 is a longitudinal sectional view fragmentarily through one of the cutter assemblies.

25 Figure 6 is a vertical sectional view taken substantially on the line 6—6 of Figure 1.

Figure 7 is a perspective view of one of the drawbars.

30 Referring to the drawings wherein like numerals designate like parts, it can be seen that numeral 5 represents the drying rolls of the upper flight, while numeral 6 denotes the rolls of the lower flight, these rolls 5 and 6 being in horizontal offset relation.

35 A cutter assembly generally referred to by numeral 7 is preferably mounted on the frame over each of the lower rolls 6 and each of these cutter assemblies consists of an elongated tube 8 having the square passageway 9 extending longitudinally therein. The side of the tube 8 is formed with a longitudinally extending slot 10 through which projects the bushing 11 from the shell of the motor 12, which motor is located on a slide plate 13 capable of sliding on the bottom of the passageway 9. An ear 14 extends laterally from the motor 12 and to this is pivotally connected as at 15, the drawbar 16.

40 The armature shaft 17 of the motor 12 extends through the bushing 11 and is threaded

5 at its outer end. This threaded outer end projects through the cutter disk 18 and nuts 19 on this threaded portion of the armature shaft fixes the location of the cutter disk 18 on the armature shaft.

A semi-circular shaped grill 20 serves as a guard for the upper portion of the disk 18, this guard having hub members 21 and 22. The hub member 21 has the outer end of the armature shaft journaled therein, while the hub member 10 22 fits over the outer end of the bushing 11 and is preferably keyed or pinned thereto.

Leg members 23 extend downwardly from the ends of the tube 8 and are attached or secured in some suitable manner to the drier frame 24.

15 Obviously when the paper strip 25 buckles or jams in the drier, the same can be readily severed by sliding the motor 12 longitudinally in the adjacent tube 8 with the motor operating the cutter blade 18.

20 While the foregoing specification sets forth the invention in specific terms, it is to be understood that numerous changes in the shape, size and materials may be resorted to without departing from the spirit and scope of the invention 25 as claimed hereinafter.

Having described the invention, what is claimed as new is:

1. A web cutter comprising an elongated stationarily mounted tube having a slot extending 30 longitudinally in the side thereof, a motor slidably longitudinally in the tube and having an armature shaft protruding through the slot, and a cutter carried by the outer end of the armature shaft, and an elongated rod extending into the tube and pivotally attached to the motor and adapted to move the motor longitudinally in the said tube.

2. A web cutter of the character described comprising an elongated stationarily mounted tube having a slot extending longitudinally in the side thereof, a motor slidably disposed in the tube, means for moving the motor longitudinally in the tube, a bushing projecting from the motor and through the slot, said motor including 40 an armature shaft projecting through the bushing and beyond the outer end thereof, a knife carried by the outer end of the armature shaft, and a guard partly encompassing the knife and having one side thereof secured to the outer 45 end of the bushing.

CHARLES C. SHACKELFORD.
